UNITED STATES PATENT OFFICE.

ROLLAND H. POTTER, OF FAIRFIELD, NEBRASKA.

DESIGN FOR A TOY SAVINGS BANK.

Application filed September 10, 1924. Serial No. 10,732. Term of patent 7 years.

To all whom it may concern:

Be it known that I, ROLLAND H. POTTER, a citizen of the United States of America, residing at Fairfield, in the county of Clay and State of Nebraska, have invented a new, original, and ornamental Design for a Toy Savings Bank, of which the following is a specification, reference being had to the accompanying drawing, forming a part hereof.

The drawing is a perspective view of a toy savings bank showing my design.

I claim:

The ornamental design for a toy savings bank, as shown.

ROLLAND H. POTTER. [L. s.]
